DESIGN FOR A FLUORESCENT FIXTURE OR SIMILAR ARTICLE

George A. Kotcher, Detroit, Mich.

Application September 14, 1942, Serial No. 108,228

Term of patent 7 years

To all whom it may concern:

Be it known that I, George A. Kotcher, a citizen of the United States and a resident of Detroit, Wayne County, Michigan, have invented a new, original, and ornamental Design for a Fluorescent Fixture or Similar Article, of which the following is a specification, reference being had to the accompanying drawing, forming part thereof.

Figure 1 is a perspective view of a fluorescent fixture or similar article showing my new design.

Figure 2 is a front elevational view, and Figure 3 is an end elevational view of the same. The characteristic features of my design reside in the portions shown in full lines.

I claim:

The ornamental design for a fluorescent fixture or similar article, as shown and described.

GEORGE A. KOTCHER.
